UNITED STATES PATENT OFFICE.

WILLIAM GEORGE CANNON, OF LONDON ROAD, SOUTHWARK, COUNTY OF SURREY, ENGLAND.

STEAM-RADIATOR.

SPECIFICATION forming part of Letters Patent No. 310,375, dated January 6, 1885.

Application filed July 30, 1884. (No model.) Patented in England May 29, 1884, No. 8,395.

To all whom it may concern:

Be it known that I, WILLIAM GEORGE CANNON, a subject of the Queen of Great Britain, residing at 106 and 107 London Road, Southwark, in the county of Surrey, England, gas and hot-water engineer, and manufacturer of hot-water apparatus, have invented certain new and useful Improvements in Steam-Radiators, (for which I have obtained a patent in Great Britain, No. 8,395, bearing date 29th of May, 1884,) of which the following is a specification.

The object of my invention is to construct hot-water and steam coils or radiators for heating purposes in an improved manner, and with increased facilities for making the joints.

In carrying out my invention, I usually cast triple pipes in one casting, the main body of which consists of three pipes, and the two ends of which three pipes unite and form one neck the area of which is about equal to the united areas of the three pipes.

Instead of grouping three pipes together, four or more may be similarly grouped for the same object, and in all cases, if necessary, a cross water-way can be arranged through the center of the group of tubes. The neck or junction at each end of the group of pipes is provided with a flange or shoulder, upon which a vulcanite, asbestos, or other joint-packing is placed to make a steam or water tight joint. The cross-sectional form of the tubes may be rectangular, elliptical, circular, or otherwise, the object being to present a large heating-surface to the atmosphere to be warmed. The ends, however, are (by preference) circular; but I do not confine myself to that form, as other forms may be used. These tubes are connected to socket-tubes, which are placed at right angles thereto, the multiple tubes being usually placed in a vertical position and the socket-tubes in a horizontal position; but these positions may be reversed or otherwise varied according to circumstances. The socket-tubes are made with suitable socket or stuffing boxes, which fit the necks of the grouped or multiple tubes, and the joint is made by means of a ring of vulcanite, asbestos, or other suitable packing. The center pipe of the group

is further utilized by passing a rod through 50 the same, the ends of which rod are tapped to receive a nut; or one end may have a head formed thereon, and the other end may be tapped to receive a nut. The ends of this rod pass through a suitable hole in the outer or 55 socket tube at the top and bottom. In some cases the rod is provided with a nut and washer to make a joint and keep the multiple-tube ends in the sockets, and in other cases for the same purpose a countersunk boss is provided 60 in the socket-pipe into which the rod is tapped or otherwise attached, so as to make a sunk connection and leave the outside of the socket-pipe fair and flush without projections. When a number of grouped tubes are connected to 65 together, the tie-rods may be omitted from some of the groups, and a tie-rod may be fitted to every second or third group only, unless the pressure requires a greater number of tie-rods. The several connections may also be made 70 with iron-cement joints by making the joints of sufficient length, in which case the tie-rods may be dispensed with. The several pipes, rods, nuts, washers, and other articles may be made with any suitable materials, cast-iron 75 being preferable to save expense; and in order that my said invention may be clearly understood, reference is hereby made to the accompanying drawings, in which similar letters of reference indicate corresponding parts. 80

Figure 1 is a sectional diagram, in which *aa* is a triple-loop pipe. *b* is the socket-pipe. *c c'* are the sockets, the method of forming the joint being clearly shown. *d* is the elastic packing. *e* is a nut, which is tapped to the 85 tension-rod *f*, a washer, *g*, being inserted between the nut and the socket-pipe. One end of the tension-rod *f* may be tapped into a boss formed in the socket-pipe, as shown at *h*, if preferred. 90

Fig. 2 is an external view of one end of a triple-loop pipe attached to the socket-pipe. Fig. 3 is a section on the line *xx* of Figs. 1 and 2. Fig. 4 is a plan of the socket shown at *c'* in Fig. 1, and Fig. 5 is a section showing the usual 95 form of the socket-pipe. Fig. 6 shows my method of grouping five, or any other number of pipes together, and a cross communi-

heating-chamber is shown at *k* for assisting the circulation and steadyng long pipes. Fig. 7 shows the method of countersinking the tension-rod nuts in order to render the 5 outside flush and avoid projections.

It is obvious that my said invention is equally applicable to the use of steam for heating purposes.

I am aware that radiators have been composed of sections comprising several pipes emerging at one end into a single pipe coupled to horizontal connecting-pipes, and I am also aware that the sections of a radiator have been secured together by rods passing through the 15 interior of the pipes. Such features, therefore, I do not broadly claim.

Having now particularly described and ascertained the nature of my said invention and in what manner the same is to be performed, I declare that what I claim is—

1. In heating apparatus, the combination, with socket-pipes, of multiple pipes merging

into one at each end, and a tension-rod passing through one branch of the multiple pipes, and having its ends connected to the socket-pipes, 25 substantially as described.

2. In heating apparatus, the combination of the pipes *b*, having sockets, and the multiple pipes merging into one at each end and formed with transverse communicating ways or chambers, and the ends of the pipes fitting the said sockets with the tension-rod passing through one branch of the multiple pipes and having its ends connected to the socket-pipes, substantially as described. 30

In testimony whereof I have hereunto set my hand this 15th day of July, 1884. 35

WILLIAM GEORGE CANNON.
